PREPARATION OF DIAKENYL SULFIDES

Robert T. Armstrong, Johnson City, Tenn., assignor to United States Rubber Company, New York, N. Y., a corporation of New Jersey

No Drawing. Application April 11, 1945,
Serial No. 587,831

4 Claims. (Cl. 260—608)

1 This invention relates to the method of preparing sulfides of olefin hydrocarbons, and to the resulting products.

Heretofore it has been necessary to use as starting materials olefinic halides for the preparation of olefin sulfides, and in such cases the yields have been poor. An object of this invention is to use the olefin hydrocarbons directly as a starting material with resulting good yields of the sulfides. Further, it has been found that the reaction of olefins, with elemental sulfur, in the absence of zinc or similar metal in combination, produces alkyl alkenyl polysulfides rather than dialkenyl sulfides. By a dialkenyl sulfide is meant a monomeric compound consisting of sulfur bonded to two alkenyl groups. They subscribe to the formula $R-S_n-R$ where n is a whole number from 1 to 2, and R is an olefinic radical. Alkenyl is used in the usual sense to refer to a monovalent radical containing an ethylenic linkage.

The chemicals are prepared by a method which consists in interacting any olefinic hydrocarbon containing from 3 to 12 carbon atoms and comprising the group

with elemental sulfur, in the presence of zinc or similar metal in combination, and a nitrogen-containing compound which belongs to the class of rubber vulcanization accelerators.

There should be present at least one molecular proportion of zinc or similar metal in combination for each two molecular proportions of the olefin; an excess tends to minimize undesirable side reactions. The molecular proportion of the sulfur should be at least 1.5 atomic proportions for each molecular proportion of the olefin. The proportion of the nitrogen-containing accelerator need be only sufficient to furnish a catalytic effect, that is, a small amount; .01 to .2 molecular proportion based on the olefin are generally sufficient. Most of the accelerator may be recovered unchanged. The amount of the accelerator is therefore not critical.

The zinc or similar metal is preferably in the form of a zinc salt of the fatty acid, generally one comprising from 3 to 18 carbon atoms. The salt may be added as such or formed in situ, as where zinc oxide is added with the fatty acid. The reaction for preparing disulfide may be represented by the following equation:

R is an aliphatic radical containing from 3 to 17 carbon atoms.

2 Examples of olefins are propene, the butenes, the amenes, the hexenes, the heptenes, the octenes, the nonenes, the decenes, the undecenes, and the dodecenes. Where more than one member is referred to the intention is to include each member of the class which contains a hydrogen atom attached to the carbon atom which is alpha to the double bond.

Among the sulfides may be mentioned 6,6'-di-
10 thiobis (5-methyl-4-nonene), and 6,6'-thiobis (5-methyl-4-nonene), 2-butenyl monosulfide and disulfide, and 2-methyl-2-butene monosulfide and disulfide.

The sulfides of this invention are clear liquids
15 possessing a persistent garlic-like odor and may be used as insecticides, fumigants, and as intermediates in the preparation of dyes, pharmaceuticals, resins, etc.

20 Although the reactive form of the zinc in the reaction appears to be the salt of the organic acids of the fatty acid series, such as zinc propionate, zinc stearate, etc., it is possible to substitute zinc oxide for a portion of the zinc salt only to such extent that the rate of the reaction is not impaired so that undesirable side reactions occur. Also, the salt can be formed in the reaction by introducing the proper amounts of the zinc oxide and of the acid.

25 In place of zinc, other members of the so-called magnesium-zinc family of elements (see page 344 of Mellor's "Modern Inorganic Chemistry," published by Longman, Green & Company, 1922), which family includes besides zinc, cadmium, magnesium, and mercury—may be used in place of the corresponding zinc compounds.

30 2-mercaptopbenzothiazole and other thiayl sulfides are exemplary of the so-called vulcanization accelerators which are useful in promoting the reaction of sulfur with olefin according to my invention; others, called thiuram sulfides, such as tetramethyl thiuram sulfide, tetramethyl thiuram disulfide, and ureas such as diphenylthiourea, and amines, such as dibenzylamine, diphenylguanidine, and triamylamine, as well as other nitrogen-containing accelerators of rubber vulcanization can be used.

35 The reaction takes place slowly at room temperature and increases in rate with increasing temperature. The maximum temperature is limited only by the temperature at which thermal decomposition of the products occurs. Efficient temperatures are in the range from 90 to 180° C.

40 The following examples illustrate the invention, the parts being by weight.

EXAMPLE 1

45 A mixture of 280 parts of 5-methyl-4-nonene, 64 parts of sulfur, 8 parts of 2-mercaptopbenzothiazole, 56 parts of zinc propionate, and 106 parts of zinc oxide is heated for 24 hours at 120° C. The

reaction product is centrifuged to remove the insoluble material and is then washed with concentrated ammonium hydroxide to remove mercaptans. Unreacted sulfur is removed by heating the residue with an acetone-water solution of sodium sulfite. The high-boiling product is distilled in a molecular still, and is found to consist mainly of a mixture of the dialkenyl disulfides formed by substitution of sulfur at an *a*-methylene group of the olefin, together with a small amount of monosulfide.

Analyses

Disulfide from methylnonene:

Found: C, 70.8; H, 10.6; S, 18.7, 19.1%; $[\eta]_{20}^D = 1.502$.

Calc. for $C_{20}H_{38}S_2$: C, 70.1; H, 11.2; S, 18.7.

Monosulfide from methylnonene:

Found: S, 11.6; $[\eta]_{20}^D = 1.482$.

Calc. for $C_{20}H_{38}S$: S, 10.3.

EXAMPLE 2

A mixture of 300 parts of trimethylethylene, 90 parts of sulfur, 150 parts of zinc oxide, 85 parts of zinc propionate and 12 parts of 2-mercaptopbenzothiazole is heated at 130° C. for 16 hours. The product, purified as in Example 1 above, is found to consist of approximately equal parts of the alkenyl monosulfide and disulfide, which are then separated by fractional distillation under vacuum.

Analyses

	B. P.	$[\eta]_{20}^D$	Sp. gr. 25°/4°	Per Cent C	Per Cent H	Per Cent S
Monosulfide from trimethylethylene:						
Found	60-68/5 mm.	1.497	0.892	70.5	11.1	18.4
Calc. for $C_{10}H_{16}S$				70.6	10.6	18.8
Disulfide from trimethylethylene:						
Found	65-60/1 mm.	1.530	0.975	59.9	9.4	31.7
Calc. for $C_{10}H_{16}S_2$				59.4	8.9	31.7

EXAMPLE 3

Butene-2 is reacted with sulfur in a manner analogous to that of Examples 1 and 2 above and yields a mixture of the 2-butenyl mono- and disulfides.

Analysis of monosulfide: Calc. for $C_8H_{14}S$ —S, 22.5%; found: S, 22.4%; boiling point, 62-65° at 7 mm.; index of refraction, $[\eta]_{20}^D = 1.4921$ to 1.4941.

Having thus described my invention, what I claim and desire to protect by Letters Patent is:

1. A method of preparing dialkenyl sulfides subscribing to the formula $R-Sn-R$ where R is an olefinic radical, and n is an integer from 1 to 2, which comprises reacting 2 molecular proportions of an olefinic hydrocarbon containing from 3 to 12 carbon atoms and containing the structure

with at least 1.5 atomic proportions of elemental sulfur, in the presence of at least 1 molecular proportion of a metal salt of a saturated fatty acid having from 3 to 18 carbon atoms, the metal thereof being selected from the magnesium-zinc family of elements of the periodic table, and as catalyst a small but effective amount of a nitrogen-containing compound recognized as a vulcanization accelerator for rubber.

2. A method of preparing dialkenyl sulfides subscribing to the formula $R-Sn-R$ where R is

an olefinic radical, and n is an integer from 1 to 2, which comprises reacting, at a temperature in the range from about 90° C. to about 180° C., 2 molecular proportions of an olefinic hydrocarbon containing from 3 to 12 carbon atoms and containing the structure

with at least 1.5 atomic proportions of elemental sulfur, in the presence of at least 1 molecular proportion of a metal salt of a saturated fatty acid having from 3 to 18 carbon atoms, the metal thereof being selected from the magnesium-zinc family of elements of the periodic table, and as catalyst a small but effective amount of a nitrogen-containing compound recognized as a vulcanization accelerator for rubber.

3. A method of preparing dialkenyl sulfides subscribing to the formula $R-Sn-R$ where R is an olefinic radical, and n is an integer from 1 to 2, which comprises reacting 2 molecular proportions of an olefinic hydrocarbon containing from 3 to 12 carbon atoms and containing the structure

with at least 1.5 atomic proportions of elemental sulfur, in the presence of at least 1 molecular pro-

portion of zinc salt of a saturated fatty acid having from 3 to 18 carbon atoms and as catalyst a small but effective amount of a nitrogen-containing compound recognized as a vulcanization accelerator for rubber.

4. A method of preparing dialkenyl sulfides subscribing to the formula $R-Sn-R$ where R is an olefinic radical, and n is an integer from 1 to 2, which comprises reacting 2 molecular proportions of an olefinic hydrocarbon containing from 3 to 12 carbon atoms and containing the structure

with at least 1.5 atomic proportions of elemental sulfur, in the presence of at least 1 molecular proportion of zinc salt of a saturated fatty acid comprising from 3 to 18 carbon atoms, and as catalyst a small but effective amount of a thiayl sulfide of a character known to accelerate the vulcanization of rubber with sulfur.
